INVENTOR

Lewis C. Mathews.

ATTORNEY

UNITED STATES PATENT OFFICE.

LEWIS C. MATHEWS, OF MALAD CITY, IDAHO.

FOUNTAIN-COME.

1,263,693.

Specification of Letters Patent. Patented Apr. 23, 1918.

Application filed June 1, 1917. Serial No. 172,263.

To all whom it may concern:

Be it known that I, LEWIS C. MATHEWS, a citizen of the United States, residing at Malad City, in the county of Oneida and State of Idaho, have invented certain new and useful Improvements in Fountain-Combs, of which the following is a specification.

My invention relates to combs and the 10 primary object thereof is to provide a fountain comb which is particularly adapted to contain hair tonic and is constructed so that the same will convey the tonic to the roots of the hair.

15 A second object of the invention is to provide a fountain comb which is very light and yet durable and which will present a neat and artistic appearance.

It is another object of the invention to 20 provide a comb of this character constructed so as to prevent the liquid from flowing from the comb while the same is being filled.

Another object resides in a fountain comb which is simple in construction, and which 25 consists of few parts and which can be easily handled and is inexpensive to manufacture.

The above general objects together with others will be fully set forth hereinafter and the inventive features explicitly defined in 30 the appended claims.

The invention embodies details of construction, formations, and arrangements, which will be specifically set forth herein-after and illustrated in the accompanying 35 drawings in which—

Figure 1 is a side elevation of a fountain comb constructed in accordance with my invention, parts being broken away.

Fig. 2 is a fragmentary view showing the 40 manner of filling the comb.

Fig. 3 is a vertical sectional view.

Fig. 4 is a fragmentary longitudinal sectional view of a modified form of tine.

My improved comb is formed from the 45 usual materials such as celluloid, hard rubber, etc.

Like characters of reference designate like parts in all of the views.

Referring more particularly to the drawings the numeral 5 designates a horizontally disposed fluid reservoir which in this instance is shown as cylindrical, but, however, it may be formed in any desired shape. Extending across one end of this reservoir 5 is 55 a wall 6. This reservoir 5 is formed with an upwardly extending extension 7 which is

for the purpose of ornamentation. Threaded in the opposite end of the fluid reservoir is a filling conduit 8 which is identical with the extension 7 in shape. Threaded on the upper end of this conduit 8 is a cap 9. Formed on the reservoir 5 and extending longitudinally thereof is a rib 10, one end of which is integral with the extension 7.

Also formed on the fluid reservoir 5 and at a point directly opposite the rib 10 is a comb proper which includes the body 11 and the usual tine 12.

Each of the tines 12 is provided with a longitudinal duct 13 which communicates with the reservoir 5. These openings 6 are relatively small in diameter and extend the entire length of the tines and open upon the small end of the same as clearly illustrated in Fig. 3.

The filling conduit 8 is provided with extensions or lugs 14 and 15 which abut the adjacent end of the rib 6 and comb proper respectively when the parts are in operative position.

Fig. 4 illustrates a modified arrangement of the longitudinal opening in the tines. In this form of the invention the lower end of each of the openings open upon one of the longitudinal faces of the tines and in close proximity to the points or narrow ends thereof.

It will be manifest that the cylindrical reservoir 5 serves as a gripping member whereby to manipulate the comb as well as to contain the liquid. It will be also seen that when it is desired to fill the reservoir it is only necessary to remove the cap 9 and to rotate the filling tube to the position shown in Fig. 2.

From the above description it will be seen that I have provided a fountain comb which is very light, thereby facilitating the manipulation of the same and which does not consist of awkward and cumbersome parts.

This description is merely illustrative and I wish to here state that the invention is susceptible to various modifications and alterations that may be embodied in the here-with appended claims.

What is claimed is:

1. In a fountain comb, a reservoir, and upwardly extending ornamental extension formed at one end thereof, a wall extending across the reservoir adjacent the extension, a filling tube mounted in the opposite end of the reservoir, a filling tube being of the

- same shape as the extension, and a plurality of tines carried by the reservoir and each having a longitudinal opening therein which extends the entire length of the same.
5. 2. A comb of the character described comprising a cylindrical reservoir, an upwardly extending extension formed at one end thereof, a filling tube mounted in the opposite end of the reservoir, the filling tube being of the same shape as the extension, and a comb formed in the tube and extending longitudinally thereof, each of the tines being provided with a longitudinal opening which communicates with the reservoir and 10 opens upon the outer face of the tines.
3. A comb of the character described, comprising a reservoir, an ornamental extension formed at one end thereof, a rib formed upon the reservoir and extending 15 longitudinally thereof, a comb body fixed to the tube, a plurality of tines carried thereby and provided with longitudinal openings which communicate with the reservoir and extend the entire length of the 20 tines, a filling tube detachably engaged with the opposite end of the reservoir, and lugs 25

carried thereby one of which abuts one end of the longitudinal rib while the other abuts one end of the comb body when the comb is assembled for use.

30

4. A fountain comb, including a hollow body portion closed at one end, a substantial L-shaped filling tube rotatably mounted in the opposite end thereof, a closure for said tube, and a plurality of hollow teeth 35 carried by said body portion.

35

5. A fountain comb, including a hollow body portion closed at one end, a filling tube having offset ends, one of said ends being threadedly engaged with the open end of the body portion, a cap threaded upon the opposite end of the tube, and a plurality of teeth carried by said body portion, each of said teeth having a longitudinally extending bore communicating with the interior of the 40 body portion.

40

In testimony whereof I affix my signature in presence of two witnesses.

LEWIS C. MATHEWS.
